COMBINED FOOD PACKAGING AND COOKING CONTAINER

Bruce C. Hartman, Chicago, Ill., assignor to Booth Fisheries, Division of Consolidated Foods Corp., Chicago, Ill., a corporation of Maryland

Filed Sept. 11, 1969, Ser. No. 19,110

Term of patent 14 years

Int. Cl. D9—04

U.S. Cl. D9—219

FIG. 1 is a top perspective view of a combined food packaging and cooking container showing my new design;

FIG. 2 is a top plan view thereof;

FIG. 3 is a front elevational view thereof;

FIG. 4 is a side elevational view thereof as seen from the left of FIG. 2; and

FIG. 5 is a side elevational view thereof as seen from the right of FIG. 2.

The bottom of the design is substantially plain and unornamented.

I claim:

The ornamental design for a combined food packaging and cooking container, substantially as shown and described.
